PROCESS OF AND APPARATUS FOR PRODUCING SHEET GLASS

James C. Blair, Toledo, Ohio, assignor to Libbey-Owens-Ford Glass Company, Toledo, Ohio, a corporation of Ohio

Application June 21, 1928. Serial No. 287,099

7 Claims. (Cl. 49—3)

The present invention relates to a process of and apparatus for producing sheet glass, and more particularly to improvements therein tending to facilitate, expedite and improve generally the manufacture thereof.

An important object of the invention is the provision of a process and apparatus whereby molten glass may be reduced to sheet form at one speed, after which the sheets may be moved at a different rate of speed through an annealing leir so that the length of the leir need not be unnecessarily long.

Another object of the invention is the provision of such an improved process and apparatus, wherein the sheet is formed at a relatively rapid rate of speed and carried ahead and passed into an annealing leir at substantially the same speed, the sheet being conveyed through the leir upon rolls normally positively driven at a speed less than the speed at which the sheet is introduced into the leir, said rolls having means associated therewith whereby they may be driven by the sheet when the speed of said sheet exceeds that at which said rolls are normally positively driven.

Another object of the invention is to provide an annealing leir including a plurality of annealing sections and sheet glass forming means whereby molten glass may be reduced to sheet form, the construction being such that the sheet forming means may be adjusted in a manner that the sheets may be fed into the desired section of the annealing leir.

A further object of the invention is to provide a double-deck annealing leir and sheet glass forming means whereby molten glass may be rolled to sheet form, said forming means being adjustable in such a manner that the sheets will be alternately fed into the top and bottom of the double-deck leir.

Other objects and advantages of the invention will become more apparent during the course of the following description when taken in connection with the accompanying drawing.

In the drawing forming a part of this application and wherein like numerals are employed to designate like parts throughout the same,

Fig. 1 is a vertical longitudinal section illustrating diagrammatically a portion of my improved construction.

Fig. 2 is a section taken on line 2—2 of Fig. 1.

Fig. 3 is a sectional detail view of a portion of the apparatus, and

Fig. 4 is a section taken on line 4—4 in Fig. 3.

The improved construction herein provided has been designed primarily for the production of

plate glass blanks, although it can also be used to produce ordinary window glass if desired. Broadly speaking, the invention contemplates the reduction of molten glass to sheet form at a relatively high rate of speed so that the molten glass will contact with the sheet forming mechanism for only a relatively short time, the sheet being then transferred to an annealing leir which is so designed that the speed of travel of the sheet can be materially reduced and passed therethrough so that the length of the leir will not be unnecessarily long. The molten glass supplied to the rolling mechanism may be produced in individual pots or supplied thereto from a tank furnace.

Referring to Fig. 1, the numeral 5 designates the upper roll of the sheet forming mechanism supported and journaled at either end in a bracket support 6. A gear 7 connected to a suitable source of power is associated with the shaft of roll 5 whereby to drive the same. Mounted beneath the roll 5 is the second or lower roll 8 of the sheet forming mechanism, the said lower roll being carried by a hanging bracket 9, suspended by the means 10 from the shaft 11 of roll 5. In this manner, the lower roll 8 may be moved about the axis of rotation of the upper roll 5.

The rolls 5 and 8 are positioned with respect to one another in a manner to create a sheet forming pass 12 therebetween which controls the thickness of the glass sheet 13 produced, the size of the sheet forming pass 12 being determined by the adjustment of the nut 14 on the shaft 15. The nut 14 bears against a resilient spring 16 which is sufficiently strong to normally force the rolls 5 and 8 together as close as the adjustment of the nut 14 will permit. The springs 16 at each end of the rolls are provided, however, to allow for a separation of the rolls should foreign matter or exceptionally thick cold pieces of glass enter the sheet forming pass. In allowing for a separation of the rolls in this manner, serious injury to the rolls may be prevented when such foreign matter does come in contact therewith. Each of the rolls 5 and 8 is preferably provided with a central bore 17 through which a temperature control medium may be circulated. The lower roll 8 is also positively driven and may derive its power from a gear 18 in mesh with a gear 19, which gear is keyed to the shaft 11 of upper roll 5. The gear teeth are long enough to permit relative adjustment between the rolls and still have the gears properly meshed.

A slab or glass receiving table 20 and a second slab or table 21 are arranged at opposite sides

of the sheet forming pass 12 and are preferably carried by the bracket 9. The portion 22 indicated in section in Fig. 2 represents the connection between the slabs and the bracket 9 and due 5 to this arrangement, the slabs 20 and 21, together with the roll 8, are all movable as a unit about the axis of rotation of roll 5. A plurality of rolls 23 are also associated and movable with the bracket 9, the rolls 23 being positively driven by means 10 of a chain 24 trained over a drive sprocket 25 keyed to the shaft of roll 8 and driven thereby.

A segment 26 carried by the bracket 9 meshes with a worm 27 and upon rotation of this worm, the lower roll 8 and associated parts 20, 21 and 15 23 may be tilted about the roll 5 as desired. The worm 27 may be rotated by means of a shaft 28 to which is connected a suitable handle or other operating mechanism. In Fig. 1, the lower roll 8 and associated parts are represented in one position in full lines and in another position in dotted lines.

As shown in Fig. 1, the annealing leir 29 is composed of a plurality of annealing sections or decks 30 and 31. Each section or deck of the 25 leir is provided with a plurality of sheet supporting and conveying rolls 32, and to prevent broken glass from the upper deck entering the lower deck a partition wall or screen 33 may be used. Mounted between the sheet forming rolls 30 5 and 8 and the leir 29 is a pair of sheet conveying tables 34 and 35 respectively, each conveying table being composed of a plurality of horizontally arranged rolls 37. The rolls of the upper conveying table 34 are in horizontal alignment 35 with the rolls 32 in the upper deck 30 of leir 29, while the rolls of the lower conveying table 35 are in horizontal alignment with the rolls 32 of the lower deck 31 of leir 29. The rolls of each of the conveying tables 34 and 35 40 are positively driven by means of chains or the like 36 trained about suitable gears carried on the roll shafts, and it is preferred that the peripheral speed of the rolls 37 comprising the conveying tables, be substantially identical with the peripheral speed of the sheet forming rolls 5 and 8.

In the operation of the apparatus, the lower forming roll 8, together with its associated parts, are first moved about the axis of the upper forming roll 5 so as to bring the rolls 23 into proper 50 cooperative relation with the desired conveying table 34 or 35. For the purposes of illustration the rolls 23 are shown in full lines in Fig. 1 in cooperative relation with the upper conveying table 34. A mass or charge of molten glass 38 is then adapted to be deposited upon the receiving slab or table 20. Since this table is in an inclined position, the glass will tend to flow 55 downwardly to the sheet forming pass 12 and upon rotation of the forming rolls, the glass will be fed through the sheet forming pass and thus reduced to a sheet 13 of the desired thickness, this sheet being then passed over the slab 21 and rolls 23 onto the conveying table 34 and thence into the upper deck 30 of leir 29. The lower forming roll 8 and its associated parts are then moved to bring the rolls 23 into cooperative 60 relation with the lower conveying table 35, as indicated by the broken lines in Fig. 1, and a second sheet is rolled from another charge of glass 38, the second sheet being fed into the lower deck 31 of leir 29. Thus, the sheets formed 65 are fed alternately into the upper and lower decks of the leir.

It is preferred that the peripheral speed of

the sheet forming rolls be relatively fast so that the mass of molten glass 38 will be quickly reduced to sheet form. This is desirable for several reasons. In the first place, the glass 38 will not become unduly chilled before it is reduced 80 to sheet form. Secondly, the contact of the glass with the relatively cool forming rolls will be relatively short and therefore the surfaces of the glass sheet will not be unduly marred, and thirdly, by rolling the glass at a relatively rapid 85 rate, production can be speeded up.

As above stated, the peripheral speed of the rolls 37 of the conveying tables 34 and 35 is substantially identical with the peripheral speed of the sheet forming rolls. The length of the conveying tables is preferably such that when the sheet leaves the same it will have become substantially set and capable of sustaining its own weight. However, if the glass sheet is passed 90 through an annealing leir at the same speed at which it is formed, the length of the annealing leir would be considerable. Therefore, the annealing leir therein provided is of a character 95 that the glass sheets can be formed rapidly and annealed slowly.

To allow for a change in the speed of travel of the sheet as it enters the leir, the first leir rolls at the intake end of the leir are provided with overrunning clutches, the constructional details of which are illustrated in Figs. 3 and 4. The 105 overrunning clutch comprises a sleeve 38 keyed to the shaft 39 of the roll 32, the sleeve 38 being provided with ratchet teeth 40. Encircling the sleeve 38 is a ring 41 through which extends pivot pins 42, screw threaded at one end as at 43 to 110 prevent accidental displacement thereof. The pins 42 are adapted to carry pawls 44 and also a sprocket wheel 45. The ring members 46 and set screws 47 are designed to prevent accidental displacement of the ring 41 and associated parts. 115 The sprocket wheel 45 has trained thereover a suitable sprocket chain, not shown, which drives the roll in the direction indicated by the arrow in Fig. 4. Normally, the pawls 44 engage the teeth 40 on sleeve 38 to positively drive the rolls 120 32. In the event, however, that the speed of the sheet exceeds the peripheral speed of the rolls, due to frictional contact between the sheet and roll, the sheet is allowed to drive the roll faster than it is positively driven. When this occurs, 125 the pawls 44 simply ride freely over the teeth 40 on sleeve 38.

By providing the intake end of the leir with rolls driven in this manner, the sheet 45 will enter the leir at a relatively high speed and will 130 gradually lose its speed until it is carried forward at the speed at which the leir rolls are positively driven.

If but a single leir were to be used and the sheets were rolled one after the other, it will be 135 readily apparent that the sheets would soon pile up on one another. To permit a constant rolling of molten glass into sheet form, the double-deck leir 29 is provided and by moving the lower forming roll 8 and associated parts into cooperative 140 relation alternately with the conveying tables 34 and 35, a sheet can be fed first into the upper deck of the leir and then into the lower deck. Where individual pots are used to supply 145 the molten glass to the sheet forming mechanism, one pot full of glass may be rolled out and fed to one section of the leir and while a second pot is being placed into position to supply the molten glass, the rolling mechanism may be adjusted 150

so that the next sheet will be supplied to the other section or deck of the leir and so on.

Where the molten glass is continuously supplied from a tank furnace, it is desirable to sever the sheet and swing the rolling mechanism for the purposes above set forth. To sever the sheet, a cutting mechanism 48 may be used. It is not necessary to stop the rolling of the sheet because as soon as the cutting mechanism 48 have been used, the rolling mechanism may be immediately adjusted and the sheet continued onto the conveying table with which the rolling mechanism is operatively associated.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In apparatus for the manufacture of sheet glass, an annealing leir including a plurality of annealing sections, upper and lower forming rolls for receiving a mass of molten glass and reducing it to a sheet of substantially predetermined thickness, means for receiving the sheet from said forming rolls, and means for adjusting the lower forming roll and receiving means as a unit about the axis of the upper forming roll to effect the delivery of the sheet to the desired section of the annealing leir.

2. In apparatus for the manufacture of sheet glass, an annealing leir including a plurality of annealing sections, a conveying table associated with each section, upper and lower forming rolls for receiving a mass of molten glass and reducing it to a sheet of substantially predetermined thickness, means for receiving the sheet from said forming rolls, and means for adjusting the lower forming roll and receiving means as a unit about the axis of the upper forming roll to bring said receiving means into operative relation with the desired conveying table dependent upon to which section of the annealing leir the sheet is to be passed.

3. In apparatus for the manufacture of sheet glass, an annealing leir including upper and lower annealing sections, a conveying table associated with each leir section outwardly thereof, upper and lower forming rolls for receiving a mass of molten glass and reducing it to a sheet of substantially predetermined thickness, a table member for receiving the mass of glass prior to its passage to the forming rolls, means for receiving the sheet from said forming rolls, and means for adjusting the lower forming roll, table member and receiving means as a unit about the axis of the upper forming roll to bring said receiving means into operative relation with re-

spect to either conveying table dependent upon to which section of the leir the sheet is to be passed.

4. In apparatus for the manufacture of sheet glass, an annealing leir including a plurality of superimposed annealing sections, a conveyor arranged exteriorly of each of the annealing sections and in horizontal alignment therewith, an adjustable sheet forming mechanism arranged in proximity to the end of the conveyors remote from the annealing leir, and means for adjusting the sheet forming mechanism to place the same in cooperative relation with any desired conveyor so that the sheet can be directed to a selected section of the leir.

5. In apparatus for the manufacture of sheet glass, an annealing leir including a plurality of annealing sections, a conveyor arranged in each section, means for driving the conveyors at a relatively slow rate of speed, a separate conveyor arranged in horizontal alignment with each of the conveyors in the leir and positioned exteriorly thereof, means for driving each of said outside conveyors at a relatively high rate of speed, an adjustable sheet forming mechanism positioned in proximity to the external conveyors, and means for adjusting the sheet forming mechanism to place it in cooperative relation with any one of the external conveyors.

6. In apparatus for the manufacture of sheet glass, an annealing leir including a plurality of annealing sections, a conveyor arranged in each section, means for driving the conveyors at a relatively slow rate of speed, a separate conveyor arranged in horizontal alignment with each of the conveyors in the leir and positioned exteriorly thereof, means for driving each of said outside conveyors at a relatively high rate of speed, an adjustable sheet forming mechanism positioned in proximity to the external conveyors, and means for adjusting the sheet forming mechanism to place it in cooperative relation with any one of the external conveyors, a portion of each conveyor arranged interiorly of the leir being provided with means that will cause the peripheral speed of said conveyor to correspond with the peripheral speed of the exterior conveyor.

7. The process of producing sheet glass, which consists in creating a sheet forming pass defined by two revolving rolls, feeding successive charges of molten glass to said pass and rolling the same to form successive sheets of glass, in passing alternate sheets formed through different annealing zones, and in changing the position of the rolls to vary the angle of the path of travel of the glass through said forming pass, dependent upon to which annealing zone the sheet is adapted to be delivered.

JAMES C. BLAIR. 125
